US0D1089225S

(12) **United States Design Patent** (10) **Patent No.:** **US D1,089,225 S**
Tang et al. (45) **Date of Patent:** **** Aug. 19, 2025**

(54) **DISPLAY SCREEN OR PORTION THEREOF WITH GRAPHICAL USER INTERFACE**

(71) Applicant: **THE LIGHT PHONE INC.**, Brooklyn, NY (US)

(72) Inventors: **Kaiwei Tang**, Brooklyn, NY (US); **Joseph Holler**, Brooklyn, NY (US)

(73) Assignee: **THE LIGHT PHONE INC.**, Brooklyn, NY (US)

(**) Term: **15 Years**

(21) Appl. No.: **29/842,614**

(22) Filed: **Jun. 14, 2022**

(57) **CLAIM**

The ornamental design for a display screen or portion thereof with graphical user interface as shown and described.

DESCRIPTION

FIG. 1 is a front view of a first embodiment of a display screen or portion thereof with graphical user interface; FIG. 2 is a front view of a second embodiment thereof; and, FIG. 3 is a front view of a third embodiment thereof. The broken lines showing the display screen form no part of the claimed design. The remaining broken lines showing portions of the graphical user interface and text form no part of the claimed design.

1 Claim, 3 Drawing Sheets
